United States Patent Office.

WILLIAM SMITH, OF PHILADELPHIA, PENNSYLVANIA.

Letters Patent No. 100,203, dated February 22, 1870.

IMPROVEMENT IN STEAM-ENGINE GOVERNORS.

The Schedule referred to in these Letters Patent and making part of the same.

To all whom it may concern:

Be it known that I, WILLIAM SMITH, of the city and county of Philadelphia, and State of Pennsylvania, have invented a new and useful Improvement in Ball-Governors for Steam-Engines; and I do hereby declare that the following is a full and exact description thereof, reference being had to the accompanying drawings and to the letters of reference marked thereon.

The nature of my invention consists of a ball-governor, the arms of which are so constructed and arranged in relation to the revolving central shaft of the governor, by means of a radial joint-connection with the same, that a free and easy tangential movement of the balls is effected, whereby the torsion of the arms, and consequent straining of the joints incidental to the usual construction of ball-governors, are prevented.

The peculiar construction and arrangement of the several parts of the governor which constitute the improvement will be understood by the following description:

In the accompanying drawings, which make a part of this specification—

Figure 1 is a plan of the improved governor.

Figure 2 is a side elevation of the same.

Figure 3 is an isometrical view of the valve-rod head E.

Figure 4 is a view of one of the arms, provided with a ball at a point at right angles with the flat end surface i of the radial projection h.

Like letters in all the figures indicate the same parts.

A is the stand, or permanent part of the governor.

The arm a, which projects from one of its sides, sustains one end of the driving-shaft B, the other end of which has any suitable support in the usual manner.

On the inner end of the said shaft there is a miter-wheel, C, which gears into the wheel C' on the lower end of the vertical shaft D, which turns in the bore b of the upright e of the stand A.

The said shaft D has a head, d, with a central opening, e, in which the head E of the valve-rod F has a free vertical movement.

It has also radial sockets, g g, which receive the radial projections h h of the arms G G of the balls H H.

The flat surfaces i of the radial projections h of the arms fit against the parallel sides j of the valve-rod

head E, which is shown in detail in fig. 3, and the shoulders k against the ends of the socket-arms l of the shaft D.

The said projections are held in place by means of pins m, with which the arms are provided, which bear in the annular grooves n of the said projections.

Projecting from the flat surfaces i of said radial projections of the arms, there are pins o which have a free play in the cross grooves p of the valve-rod head E.

One of the arms G is shown detached in fig. 4.

The operation is as follows:

When the central rod is revolved in either direction by means of its connection with the steam-engine, as above described, the balls H, acting according to a well-known law, fly off in a tangent, represented by red lines in fig. 1; and as they are thrown up to or recede from their elevated position, in their tangential movements, the radial projections h of the arms G, as they turn partly around in their sockets, cause an elevation or depression of the valve-rod F, by the altitudinal change of the pins o, in consequence of their connections with the cross grooves p of the valve-rod head E, as above described.

Thus the valve, which is not shown in the drawings, is actuated by the vertical movements of the rod F.

It must clearly appear that, as the radial projections h of the arms G have a free movement in the sockets as the balls H are thrown off tangentially, there is no straining or twisting of any of the parts in motion, and consequently but little wearing of the joints, so prominent in other ball-governors.

What I claim as new, and desire to secure by Letters Patent, is—

The combination of the arms G G, constructed substantially as described, with the head d of the central shaft D, by means of the radial sockets g g of said head and pins m m, whereby a free and easy tangential movement of the balls H H is effected, as and for the purpose hereinbefore described.

In testimony that the above is my invention, I have hereunto set my hand and affixed my seal this 19th day of April, 1869.

WM. SMITH. [L. S.]
